ALCOHOLYSIS OF LOWER FATTY ACID GROUPS IN POLYHYDROXY FATTY ESTERS

Roger L. Logan, Elkins Park, Pa., assignor to Kessler Chemical Co., Inc., Philadelphia, Pa., a corporation of Pennsylvania

**No Drawing. Application November 22, 1950,
Serial No. 197,180**

9 Claims. (Cl. 260—406)

1

This invention relates to the alcoholysis of lower fatty acid groups in polyhydroxy fatty acid esters.

The formation of polyhydroxy fatty acid esters is well known in the art. Thus, it is known to hydroxylate fatty materials using performic or peracetic acid as the hydroxylating agent. The lower fatty acid groups thus formed in the hydroxylated product are conventionally removed by alkaline saponification, followed by acid hydrolysis or by high pressure hydrolysis with water.

Unfortunately, in the case of esters, the removal of the lower fatty acid groups by these methods results in the removal of the terminal alcohol group. It is, therefore, necessary to re-esterify, which is a long and expensive process.

Thus, for example, it is well known to treat an ester of oleic acid with performic acid to form a mixture of esters of 9-formoxy-10-hydroxy stearate and 10-formoxy-9-hydroxy stearate. Alkaline saponification followed by acid hydrolysis readily removes the formoxy groups, but also removes the terminal alcohol group. Thus, it is necessary to re-esterify to replace the terminal alcohol group.

An unexpected advantage of this invention is that it permits the formation of esters of polyhydroxy fatty acids with long chain alcohols or glycols without the danger of interesterification which is present when the heretofore used methods of reacting a long chain alcohol or glycols with polyhydroxy fatty acids are used. As a result of the method of this invention, it is possible to react a long chain alcohol with an unsaturated fatty acid and then hydroxylate with, for example, performic or peracetic acid to form the formoxy or acetoxy compounds. The method of this invention provides for the removal of the formoxy or acetoxy groups without removing or substituting the terminal alcohol group.

Obviously, by this method a much purer product can be achieved since there is no chance for the glycol groups in the polyhydroxy acid to react with terminal acid groups.

The broad object of this invention is, therefore, to remove lower fatty acid groups from esters of polyhydroxy fatty acids without removing or replacing the terminal alcohol group.

Broadly speaking, the method in accordance with this invention comprises reacting an ester of a polyhydroxy fatty acid esterified by an alcohol at the terminal group and esterified at a hydroxyl group with a fatty acid group, with an alcohol and distilling off the ester formed with

2

the lower fatty acid group. The reaction is illustrated by the following specific example:

Preferably, carrying out the method in accordance with this invention, dry alcohol is added to a hydroxylated ester of a fatty acid so that the boiling point of the mixture is maintained between 60° C. and 150° C. As the newly

20 formed between 80 °C. and 150 °C. As the newly formed ester distills off, more alcohol is added. The reaction starts readily if all of the ingredients are dry and proceeds to completion. Any standard distillation unit with a fractionating column of sufficient efficiency to separate the ester formed from the alcohol used, may be utilized.

25 It is preferred to use a small amount of catalyst such as alkali metals, their alcoholates, oxides or hydroxides, such as sodium hydroxide, potassium hydroxide, barium hydroxide, sodium metal, etc. Acid catalysts such as sulfuric acid and sulfonic acids may be used. The catalysts may be used by dissolving them in the alcohol and adding the solution to the reaction. The reaction will proceed well without catalyst if all ingredients are dry.

35 The reaction may be run advantageously under pressure. Pressure increases the boiling points of the reactants and products and thus increases the reaction rate. It allows the presence of greater amounts of alcohol at higher temperatures, and aids in condensing lower esters formed.

By way of more specific example, the method in accordance with this invention can be carried out with an ester of a polyhydroxy fatty acid containing lower fatty acid groups such as, for example, an ester in which the terminal ester group may be any alcohol, as, for example, methanol, butanol, propanol, stearyl alcohol, oleyl alcohol or an octyl alcohol such as 2-ethyl hexanol, and glycols, such as glycerol and polyethylene glycols. The lower fatty acid group may have from 1 to 5 carbon atoms, as, for example, formic, acetic, propionic, butyric or valeric acids. The fatty acid portion of the compound may have from 11 to 22 carbon atoms as, for example,

10,11 dihydroxy undecanoic acid, 9,10 dihydroxy stearic acid, tetrahydroxy stearic acid, trihydroxy stearic acid and 13,14 dihydroxy behenic acid.

The following specific examples will be further illustrative of the method in accordance with this invention:

Example 1

975 grams of a 50% mixture of methyl formoxy stearates and methyl esters of C₁₆ and C₁₈ fatty acids having a saponification number of 277, were heated in a distillation apparatus, equipped with a fractionating column. There was then added 70 grams of 99.7% methanol in which was dissolved 2 grams of sodium hydroxide pellets. The mixture boiled at about 90° C. and methyl formate formed almost immediately. The first methyl formate distilled at 38° C.; within a few minutes the vapor temperature dropped to 33° C. Most of the methyl formate was distilled off by the end of five hours of reaction. Sufficient methanol was maintained in the distillation pot to keep the temperature at from 135 to 145° C. toward the end of reaction, small amounts being added from time to time.

The temperature at the top of the fractionating column finally rose to 64° C. and stayed at this point under both reflux and distillation. The saponification number of the resulting mixed methyl esters was 192.

Example 2

900 grams of a 50% mixture of methyl formoxy stearates and methyl ester of C₁₆ and C₁₈ fatty acids were heated in a distillation apparatus. There was then added 70 grams of 99.7% methanol. The mixture boiled at about 90° C. Methyl formate formed and distilled in a few minutes after boiling started. Methanol was added slowly from time to time, and methyl formate continued to distill off.

The temperature at the top of the fractionating column rose to 64° C. and remained at 64° C. under both reflux and distillation. At this point the reaction was considered complete. The saponification number dropped from approximately 280 to 188.5. The terminal methyl group was not affected. The reaction went well in the absence of catalyst.

Example 3

To 200 grams of methyl formoxy undecanoate, saponification number 381, there was added 40 grams of methanol and .2 gram of alkane sulfonic acid. The mixture was heated in a 500 ml. flask to 65° C. and after a few minutes the methyl formate formed and was taken off at the top of a 30 cm. fractionating column. The methyl formate came over for about 45 minutes.

The temperature at the top of the fractionating column then began to rise to the boiling point of methanol. The reaction was completed in one hour and ten minutes. The final pot temperature was 95° C. The final saponification number was 253.

Example 4

To 800 grams of a mixture of butyl formoxy stearate and butyl stearate, saponification number 250, there was added 100 grams of dry methanol and .8 gram of alkane sulfonic acid. Reaction took place in a 2000 ml. flask equipped with a 30 cm. fractionating column. As soon as the

reaction temperature in the flask reached 75° C., methyl formate distilled out of the fractionating column at a temperature of 35° C.

At the end of two hours of reaction, the temperature began to rise at the top of the fractionating column to the boiling point of methanol. The reaction was completed at the end of three hours. The saponification number dropped from 250 to 171. The removal of formoxy groups was complete.

Example 5

To 800 grams of butyl formoxy stearate, saponification number 250, there was added 120 grams of n-butanol and 1 gram of alkane sulfonic acid. The reaction took place in a 2000 ml. flask equipped with a 30 cm. fractionating column. The reaction began as soon as the distillation flask temperature reached 120° C.

Butyl formate was distilled off at the top of the fractionating column. The final reaction temperature was 150° C. The reaction time was 5 hours. At the end of that time, the saponification number of the ester had dropped from 250 to 169, indicating that the removal of formoxy compounds was complete.

Example 6

200 grams of commercial glyceryl mono oleate was hydroxylated with formic acid and hydrogen peroxide. The formed glyceryl formoxy hydroxy esters, saponification number 320, were subjected to the method of this invention.

The glyceryl formoxy hydroxy esters were heated with 60 grams of methanol containing .25 gram of alkane sulfonic acid, in a 500 ml. flask to which had been attached a 30 cm. fractionating column.

Methyl formate distilled as soon as the pot temperature reached 75° C. The temperature at the top of the column was 36° C. for two hours of reaction.

The temperature at the top of the column rose, during the next hour, to 64° C. The final pot temperature was 98° C. The reaction was completed in 3 hours. The final saponification number was 173.

There was no evidence of removal or replacement of the terminal glyceryl group.

Example 7

To 350 grams of methyl formoxy dihydroxy stearate, saponification number 370, there was added 100 grams of dry methanol and .7 gram of alkane sulfonic acid. The mixture was heated in a 500 ml. flask equipped with a 30 cm. fractionating column.

Reaction started when the pot temperature reached 60° C. Methyl formate distilled off at the top of the column at 36° C. The temperature at the top of the column started to rise after one hour and five minutes of reaction and the reaction was completed in three hours and fifteen minutes. The final pot temperature was 92° C.

The final product was a good grade of methyl trihydroxy stearate and had a saponification number of 171.

Example 8

100 grams of methanol was added to 250 grams of methyl formoxy hydroxy stearate with a saponification number of 263 and 4% free acid as stearic. .1% H₂SO₄ was added as a catalyst. A 500 ml. flask was used as a distillation pot and a 30 cm. fractionating column was connected to the 75 pot. The reaction began when the distillation

pot temperature reached 64° C. The top temperature was 33° C. when the methyl formate started to distill. At the end of 2½ hours most of the theoretical methyl formate had been collected and the per cent. acid as stearic of the material in the distillation pot had dropped to 1.8. The reaction was completed in 5 hours and the per cent. acid in the distillation pot had dropped to .85. The final saponification number was 137.

What is claimed is:

1. The method which comprises heating a polyhydroxy fatty acid of from 11 to 22 carbon atoms esterified by an aliphatic alcohol at the terminal group and esterified at a hydroxyl group with a lower fatty acid having from 1 to 5 carbon atoms, reacting the thus heated ester with a lower aliphatic alcohol in order to replace the lower fatty acid radical with a hydrogen atom without disturbing the terminal group.

2. The method which comprises heating a polyhydroxy fatty acid of from 11 to 22 carbon atoms esterified by an aliphatic alcohol at the terminal group and esterified at a hydroxyl group with a lower fatty acid having from 1 to 5 carbon atoms, reacting the thus heated ester with a lower aliphatic alcohol in order to replace the lower fatty acid radical with a hydrogen atom without disturbing the terminal group and distilling off the formed ester.

3. The method which comprises heating a polyhydroxy fatty acid of from 11 to 22 carbon atoms esterified by an aliphatic alcohol at the terminal group and esterified at a hydroxyl group with a lower fatty acid having from 1 to 5 carbon atoms, reacting the thus heated ester with a lower aliphatic alcohol in the presence of a catalyst in order to replace the lower fatty radical with a hydrogen atom without disturbing the terminal group.

4. The method which comprises heating a polyhydroxy fatty acid of from 11 to 22 carbon atoms esterified by an aliphatic alcohol at the terminal group and esterified at a hydroxyl group with a lower fatty acid having from 1 to 5 carbon atoms, reacting the thus heated ester with a lower aliphatic alcohol in order to replace the lower fatty radical with a hydrogen atom without disturbing the terminal group.

atoms, reacting the thus heated ester with a lower aliphatic alcohol while maintaining the boiling point of the resulting mixture between 60 and 150° C. in order to replace the lower fatty acid radical with a hydrogen atom without disturbing the terminal group.

5. The method in accordance with claim 1, characterized in that the esterified polyhydroxy fatty acid is methyl formoxy dihydroxy stearate.

10 6. The method in accordance with claim 1, characterized in that the esterified polyhydroxy fatty acid is methyl formoxy hydroxy stearate.

7. The method which comprises heating dihydroxy stearic acid esterified by methyl alcohol at the terminal group and esterified at a hydroxyl group with formic acid, reacting the thus heated ester with a lower aliphatic alcohol in order to replace the lower fatty acid radical with a hydrogen atom without disturbing the terminal group.

15 8. The method which comprises heating dihydroxy undecanoic acid esterified by methyl alcohol at the terminal group and esterified at a hydroxyl group with formic acid, reacting the thus heated ester with a lower aliphatic alcohol in order to replace the lower fatty acid radical with a hydrogen atom without disturbing the terminal group.

20 9. The method which comprises heating dihydroxy stearic acid esterified by butyl alcohol at the terminal group and esterified at a hydroxyl group with stearic acid, reacting the thus heated ester with a lower aliphatic alcohol in order to replace the lower fatty acid radical with a hydrogen atom without disturbing the terminal group.
